TEMPERATURE REGULATING MEANS FOR LIQUID COOLED ENGINES

Filed June 18, 1927

William H. Driscoll

UNITED STATES PATENT OFFICE.

WILLIAM H. DRISCOLL, OF JERSEY CITY, NEW JERSEY.

TEMPERATURE-REGULATING MEANS FOR LIQUID-COOLED ENGINES.

Application filed June 18, 1927. Serial No. 199,728.

This invention relates to liquid cooled engines and has for its principal object the provision of means for raising and otherwise regulating the temperature of the cooling liquid so as to keep the same from freezing during cold weather and also to facilitate the starting of the engine after a rest period during which the cooling liquid may have reached a temperature lower than desirable.

While my invention is capable of use in connection with any liquid cooled engine, it is particularly applicable to the ordinary combustion engine used in automobiles and other motor vehicles.

A vast amount of study and work has been spent on the problem of keeping combustion engines properly cooled and at the present time these efforts seem to have succeeded in producing efficient radiation and cooling systems which safeguard the engine from the danger of overheating. But there is another phase of the combustion engine problem, and particularly the motor vehicle problem, which has up to the present time remained unsolved; to wit, the problem of preventing the cooling water or other liquid from freezing or approaching the freezing point after the engine or motor vehicle carrying the engine has been idle for a period in cold weather.

Heretofore owners and users of motor vehicles have sought to partially safeguard against the possibility of freezing by mixing with the cooling water some liquid having a lower freezing point, such as alcohol. This expedient, of course, partially offsets the danger of freezing, but only partially. Furthermore, it has the disadvantage that it is very easy to forget to add the alcohol at the proper time, or if not forgotten, it may be unavailable when needed.

My invention proposes the use of a heating element (in the preferred embodiment an electric heating element) which may be inserted at some point in the cooling system, such as, for example, one of the compartments of the radiator. By the provision of such a heating element, the heat emission of which may be regulated by suitable means, it is possible to convey heat directly to the cooling liquid by conduction and convection, thereby giving assurance that the liquid will

be maintained at a satisfactory temperature.

Other objects and advantages to be derived from the use of the novel features of this invention reside in the specific combination and arrangement of the parts. Others will become obvious from an inspection of the following description when read with reference to the accompanying drawings, wherein the preferred embodiment is illustrated and wherein like reference characters refer to like parts in the different views.

In the drawings Figure 1 is a front elevation view of a common type of radiator used in connection with the cooling of automotive engines, with the position occupied by my novel apparatus indicated.

Figure 2 is a side view of the radiator and the parts shown in Fig. 1.

Figure 3 is a larger view of the heating element indicated in Fig. 1.

Figure 4 is an elevation view, partly in section, of the preferred form of automatic controlling switch.

Figure 5 is a schematic representation of the preferred electrical hook-up.

Figs. 6 and 7 are modifications of the device shown in Fig. 4.

Referring to Fig. 1, reference character 1 indicates a radiator, such as is commonly used on automotive vehicles for the function of providing an exposed radiating surface in the path of the circulating cooling liquid. As shown the radiator 1 carries a multiplicity of square tubes 2 through which the atmospheric air passes, the circulating cooling liquid passing between the tubes—or the arrangement may be reversed. As the cooling liquid circulates in the water jacket of the engine (not shown) it absorbs heat from the combustible charge in the engine and then flows to the radiator 2 where the heat previously absorbed is transferred to the atmosphere through the instrumentality of the radiator as the liquid courses downwardly around the tubes and into the bottom compartment 3, from which point it returns to the engine jacket either by means of a pump or by so arranging the circuit that the expansion of the liquid by the heat absorbed in the jacket and its consequent tendency to rise causes it to circulate with sufficient rapidity.

I propose to insert, preferably in the bot-

tom compartment 3 (but not necessarily in this location) a heating unit 4, which may be permanently mounted in place in the radiator by means of a threaded base 5 (Fig. 3) provided at its end and receivable by the socket indicated at 6' (Fig. 1).

Inasmuch as in the preferred form my heating unit is electrically energized, the socket 6' will have suitable provisions for 10 the insertion of a current conducting plug or other suitable connection.

As shown in Fig. 3, by way of illustration of the preferred construction, the heating unit 4 comprises a casing 6 of suitable heat transmitting material (and preferably non-corrosive also) such as brass or nickel for example. Within the casing 6 is a non-conducting core 7 on which is wound one or more high resistance filament wires 8 suitably insulated at all points and connecting 20 with the terminals on base 5, so as to receive electric current when a circuit is closed to socket 6' and base 5.

With the provision of the elements just 25 described, and by utilizing suitable current transmitting means (such as a pair of leads 9 and 10 tapped into feed lines 11 and 12), heat may be applied to the liquid in radiator 2 by direct conduction through casing 6. 30 The heat thus transmitted to the liquid will pass by convection to all portions of the circulating system, thereby preventing the liquid from freezing or dropping to an undesirably low temperature while the engine, 35 or vehicle carrying the engine, is standing idle in a cold place, such as is usual in many garages and storerooms in the cold season of the year.

Of course the heating unit 4 is constructed 40 so as to supply substantially the desired amount of heat, but additional regulation of the heat supply may be provided by placing a clock or other time-controlled circuit-controlling switch in the circuit from feed lines 45 11 and 12 to the heating element 4. Such a switch may be set to interrupt or close the circuit at any pre-determined hour. Another means of regulation is by the temperature of the circulating liquid. Such a 50 means is illustrated in Fig. 4, where a thermostatically controlled switch is shown at 13 mounted in a housing 14 secured to the inner side of wall 15 of radiator 1.

As shown in Figure 4, the switch 13 is 55 operable by a thermal unit 17 having suitably high coefficient of expansion. This thermal unit 17 is shown exposed to the liquid in the compartment 3 of radiator 1, so as to cause movement of the rod 18 in response to changes in the temperature of the liquid. Movement of rod 18 a sufficient 60 distance to the left, as shown, throws the two arms of switch 13 (with the assistance of spring 19) away from terminal blocks 20 and 21, and movement a sufficient distance

in the opposite direction returns the two arms (again with the assistance of spring 19) to the terminal blocks 20 and 21.

These terminal blocks 20 and 21 are connected by leads, as shown, to the socket 22 70 secured in the outer shell 23 of radiator 1 and serving for the attachment of a plug 22^a connected with lead 9 in the manner suggested in Figure 1. With this arrangement (which may be varied in form and 75 construction, if desired) the engine may be left with the circuit to the heating element closed at both socket 6' and socket 22, in which event the energization of the heating element will depend upon the operation of 80 switch 13, which in turn is governed by the thermal unit 17. Thus an automatically regulable system is provided which will maintain the liquid at a desired temperature without any attention on the part of the 85 user beyond the initial act of inserting the lead plugs in the socket 6' and 22.

It may be noted that suitable means, as gasket 25 and stuffing box 26, are provided for keeping the switch housing 14 free from 90 moisture.

Figures 6 and 7 illustrate a modified construction which might be used for providing thermostatic control of the system in lieu of the construction shown in Figure 4. This 95 modification comprises a bellows 30 suitably mounted in a housing 31 secured to the wall 15 of the radiator and having formed on one side thereof an elongated tubular element 32, so disposed as to extend into the liquid 100 compartment of the radiator and constructed of a suitable heat transmitting material. The bellows and associated tube 32 may be filled to any desired point as indicated by the dash lines with some suitable liquid having a suitable vaporizing temperature so that when the liquid surrounding the tube 32 reaches a predetermined temperature, which is transmitted to the liquid in the bellows and tube 32, a portion of the liquid therein 110 will vaporize, filling the normally vacant spaces 33 and 34 and producing the exertion of a pressure against the remaining body of liquid therein and also against the walls 115 of the bellows 30. The pressure thus set up will tend to move the outer wall of the bellows against the tension of spring 35, thereby causing a movement of the pin 36 to the left. When this pin 36, as shown in Figure 120 7, has, due to the force thus exerted against it, moved a sufficient distance to the left, the enlarged central portion on the hub 37, which forms a continuation of the pin 36, will have reached a position opposite the annular spring 38 located in the carriage 39. 125 When this condition occurs it is obvious that the spring 38 will, because of its tension, snap to the opposite side of the chamber 40, carrying with it the carriage 39. The carriage 39 may be equipped with the bridging 130

member 41 which may serve as a circuit making and breaking means to bridge suitable terminals connecting with the leads 42 and 43 shown in Figure 6. With this construction it will be apparent that an alternate making and breaking of the circuit thru leads 42 and 43 can be effected in response to the reciprocation of bar 36 and hub 37, said bar and hub being in turn actuated by the alternate expansion and contraction of the outer wall of bellows 30 in response to the differences in temperature of the liquid therein.

It is to be understood that other changes in the construction, arrangement, and combination of the parts may be made without departing from the scope of this invention as described herein and as defined in the appended claims.

20 I claim:

1. In an engine cooling system comprising a radiator, a housing mounted on the shell of the radiator, contact members in said housing, a switch in the housing adapted to bridge said contact members, means in the lower compartment of the radiator and di-

rectly responsive to temperature changes of the liquid therein for opening and closing said switch, a heating unit in the lower compartment of the radiator mounted on the radiator shell and means for establishing a circuit through the heating unit, the contact members and a source of electrical energy.

2. In an automobile radiator, means for regulating the temperature of the cooling liquid therein comprising a heating unit mounted in the lower compartment of the radiator, means for establishing an electric circuit from a source of electrical energy to said heating unit, a make and break device in said circuit consisting of a housing mounted on the radiator shell, contact members in said housing, a snap switch in the housing adapted to bridge said contact members, an element having flexible walls directly responsive to temperature changes of the liquid within the radiator, and means connecting said element to the switch.

Signed at Jersey City, N. J. this 17th day of June, 1927.

25 WILLIAM H. DRISCOLL.
